UNITED STATES PATENT OFFICE.

GEORGE W. KIMBERLEY, OF CLEVELAND, ASSIGNOR OF ONE-HALF TO
FREDERICK KIMBERLEY, OF NORTH OLMSTED, OHIO.

WHIFFLETREE-HOOK.

SPECIFICATION forming part of Letters Patent No. 350,436, dated October 5, 1886.

Application filed August 23, 1886. Serial No. 211,579. (No model.)

To all whom it may concern:

Be it known that I, GEORGE W. KIMBERLEY, of Cleveland, in the county of Cuyahoga and State of Ohio, have invented certain new and useful Improvements in Whiffletree-Hooks, of which the following is a specification.

This invention has for its object to provide a simple device to be attached to the ordinary flat or round whiffletree end for securing the 10 traces thereon; and it consists of a hook covering the end of the trace and hinged to a chambered support secured to the whiffletree, containing a spring for holding the hook down, the several parts being constructed, combined, 15 and operating substantially as hereinafter described, and pointed out in the claim.

In the accompanying drawings, Figure 1 is a top or plan view of the end of a flat whiffletree having my improved trace-fastener attached. Fig. 2 is a longitudinal section of the 20 same. Fig. 3 is a top or plan view of a round whiffletree having my hook attached.

A in the several figures represents the end of a whiffletree, which may be of the flat or 25 round pattern, with or without the cockeye.

B is a semicircular case having ears b and a tail, b^2 , by which it is secured to the whiffletree with screws. In the open end of 30 said case is hinged a hook, C, the free end of which has a bend or crook with a pin-point, c , which rests in a hole in the end of the whiffletree or the cockeye in the end of the whiffletree.

Within the case B is placed a spring, D, within the coils of which is a rod, E, attached 35 to the farther end of the coil, the other end having a loop engaging with a hook, d , on the main hook C, below its pivotal joint, the end of the spring resting against a shoulder, e , in the case, the tension of the spring serving to 40 hold the hook down. The lifting of the hook compresses the spring in the act of opening it for attaching or detaching the trace.

The advantage of this device is that it can be applied to all whiffletrees now in use without 45 changing or altering them.

I am aware that whiffletree-hooks containing the same general elements have before been constructed and patented. I do not, therefore, claim the combination of these elements alone; 50 but

What I do claim, and desire to secure by Letters Patent, is—

The case B, having the ears b and provided with the shoulder or wall e , in combination 55 with a hook, C, pivoted in said case outside of said wall, and the spring D and rod E, connected with and operating in said case, as shown and described, and for the purpose specified.

GEORGE W. KIMBERLEY.
